DESIGN FOR A SINE BAR

Edwin Grant Baker, Brighton, England

Application September 17, 1943, Serial No. 111,142
In Great Britain March 11, 1943

Term of patent 7 years

To all whom it may concern:

Be it known that I, Edwin Grant Baker, a subject of the King of Great Britain, residing at Brighton, Sussex, England, have invented a new, original, and ornamental Design for a Sine Bar, of which the following is a specification, reference being had to the accompanying drawings forming part thereof.

Figure 1 is a top perspective view of a sine bar showing my new design;

Figure 2 is a bottom perspective view thereof;

Figure 3 is an elevational view of one side of the sine bar;

Figure 4 is a top plan view thereof;

Figure 5 is an elevational view of the side opposite that shown in Fig. 3;

Figure 6 is a bottom plan view thereof; and

Figure 7 is an end elevational view thereof.

I claim:

The ornamental design for a sine bar, as shown.

EDWIN GRANT BAKER.
